I. B. HOWE,

Bending Metal Bars,

No 12,098.

Patented Dec. 19, 1854.

UNITED STATES PATENT OFFICE.

ISAAC B. HOWE, OF NORTHFIELD, VERMONT.

IMPROVEMENT IN MACHINES FOR STRAIGHTENING HEAVY METAL BARS.

Specification forming part of Letters Patent No. 12,098, dated December 19, 1854.

To all whom it may concern:

Be it known that I, ISAAC B. HOWE, of Northfield, in the county of Washington and State of Vermont, have invented a new or Improved Machine for Straightening or Bending Heavy Bars of Metal, and particularly railroad-bars when laid in a track; and I do hereby declare that the same is fully described and represented in the following specification and the accompanying drawings, letters, figures, and references thereof.

In the said drawings, Figure 1 denotes a side elevation of my invention, the same exhibiting the manner in which it is applied to an iron rail for the purpose of removing a downward flexure therefrom. Fig. 2 is a transverse section taken through the operating-screw to be hereinafter described. Fig. 3 is a transverse section taken through the yoke. Fig. 4 is a transverse section, wherein is exhibited the manner in which the machine is applied to a rail for the purpose of removing a lateral bend or flexure.

In the above-mentioned drawings, A denotes a screw, which in practice may be constructed about two inches in diameter and two feet in length and having a thread cut upon it for about ten inches from its head downward. This screw operates in a female screw *r*, that is fastened to the main beam or timber B by means of a fork and a connection G, extended through the lower part of the same, as seen in Fig. 2. The screw-rod should be carried through the timber B and the said connection G and be made to rest on a bearer H, placed upon the top surface of a rail. The said timber B may be made about six feet in length and five inches in thickness. For convenience of handling it, as well as for decreasing its weight, it may be grooved out on each of its sides, as seen in Figs. 2, 3, and 4. The groove on one side also serves for the reception of the head of the part D of the yoke to move in. The said yoke is composed of two parts or stirrups *c d*, (see Figs. 1 and 3,) one of which is placed on and made to embrace the beam B, while the other is made to extend underneath the rail I and to be locked to the part C, as seen in Figs. 1 and 3. The beam or lever B is provided with a movable fulcrum F. It is made to slide upon an iron

bar L, that is fastened to the under side of the lever B. The said lever may also be provided with another such bar of metal fixed to its upper surface, as seen at M. When the instrument is applied to the rail in such manner as is exhibited by Fig. 4, small bearers K K may be adapted to the opposite sides of the rail, the stirrup *d* and the fulcrum F being made to rest against such bearers.

In using the above-described machine it is to be arranged over the rail and so that the middle of the bar B shall be over the flexure, while the fulcrum, screw, and the yoke are disposed with respect to said flexure, as seen in Fig. 1. By turning down the screw A the yoke *d* may be drawn up against the rail with power sufficient to remove the bend therefrom. It will be evident that if when the fulcrum is adjusted between the yoke and the screw and the screw so applied to the lever and the rail as to enable a person to depress the lever *a* an upward bend of the rail may easily be removed.

I am fully aware of the nature of the machine for straightening rails for which Letters Patent were granted to George Williston on November 1, A. D. 1853, such machine being a combination of a screw, strap, beam, and slides, the screw and strap being disposed in the middle of the beam, which, by bearers at its two ends, is to be supported on the rail when removing a flexure, though such machine is very different from mine, as I employ a combination of a lever and screw and apply both in a manner entirely different from that in which the rest-beam and screw of said Williston's invention is made to operate, my invention enabling me to obtain at least twice and often four times the power that can be obtained from a screw made to operate through the middle of a rest-beam and without the additional power gained by employing said rest-beam as a lever. Besides, with my invention I can readily increase or diminish the power of the lever as circumstances may require.

I do not claim the combination of a screw, strap, beam, and slides as arranged, constructed, and made to operate as described in the said patent of the said Williston; but

What I do claim is—

The combination of a lever-beam, sliding fulcrum, operating-screw, and sliding yoke or holdfast as constructed and made to operate as specified, whereby I am enabled to obtain the advantage of leverage, in combination with a screw-power for bending the rail when the machine is applied thereto, as stated.

In testimony whereof I have hereunto set my signature this 23d day of October, A. D. 1854.

ISAAC B. HOWE.
